(57) CLAIM

We claim the ornamental design for the upper for a shoe, as shown and described.

DESCRIPTION

FIG. 1 is a perspective view of an upper for a shoe of the present invention.

FIG. 2 is a side view of the upper for a shoe shown in FIG. 1.

FIG. 3 is an opposite side view of the upper for a shoe shown in FIG. 1.

FIG. 4 is a top view of the upper for a shoe shown in FIG. 1.

FIG. 5 is a front view of the upper for a shoe shown in FIG. 1; and,

FIG. 6 is a rear view of the upper for a shoe shown in FIG. 1.

The broken lines on the surface of the upper of the upper for shoe in FIGS. 1-6 show claimed stitching. The broken lines showing the sole and the periphery of the upper for shoe in FIGS. 1-6 indicates a boundary of the claimed design and form no part of the claim. The broken lines on the interior of the shoe shown in FIG. 4 form no part of the claim.
